UNITED STATES PATENT OFFICE.

JESSE A. DUBBS, OF SANTA MONICA, CALIFORNIA, ASSIGNOR TO NATIONAL HYDRO-CARBON COMPANY, OF CHICAGO, ILLINOIS, A CORPORATION OF SOUTH DAKOTA.

TREATMENT OF PETROLEUM.

1,135,506.

Specification of Letters Patent. Patented Apr. 13, 1915.

Application filed June 3, 1911. Serial No. 631,189.

To all whom it may concern:

Be it known that I, JESSE A. DUBBS, a citizen of the United States, residing at Santa Monica, in the county of Los Angeles and State of California, have invented a certain new and useful Improvement in the Treatment of Petroleum, of which the following is a specification.

My invention relates to a process for the distillation of petroleum oils, particularly the asphaltic oils such as produced in California, and to the production of asphalt and asphaltic residues.

It has special reference to the treatment of the crude asphaltic oils for the obtaining of a maximum percentage of distillate and of residual asphaltic products of varying grades, by a process generally consisting in subjecting the oil, having a small amount of moisture either in the form of water or steam, to a heat and pressure varying according to the density or gravity of the crude, and the percentage of water used or naturally present in the oil, and causing the mixture of oil and water thus heated, to expand in a vaporizing chamber, from which the distillates, as well as various grades of asphalt, are recoverable.

Petroleum oils have heretofore been subjected to pressure and heat for specific purposes, principally to prevent the liberation of any vapor while the pressure is being maintained, and thereby to cause a chemical combination of the homologous hydrocarbons, such process being productive of a more homogeneous vapor when the oil is allowed to expand in a vaporizing chamber. Such processes require a high heat and an enormous pressure to cause a vaporization of the oil, and even then the hydrocarbon molecules are not split up to a degree sufficient for a complete evolution of the inherent vapors because the expansion per molecule of oil is limited, and the different hydrocarbons existing naturally in crude petroleum will not be acted on by or respond to the expansive forces caused by the pressure, in equal measures. I do not refer to the unvaporizable constituents of the crude oil, but only to those hydrocarbon elements which, in the presence of heat and pressure, break up and become separated from the basic or more solid constituents.

I have discovered that the subjection of oil, admixed with an element of moisture having a wide expansive range when heated, such as steam or water, to a temperature ranging according to the density of the crude, from 150° F. to 600°, and under a pressure of say 50 to 300 pounds per square inch, will give a far better and increased yield of distillates, and a residual product that may be gaged for penetrability, ductility and tenacity according to the requisites of the use. When the oil thus subjected is liberated in a vaporizing chamber, the particles of oil are broken up by what may be termed the "successive" action due to the sudden liberation of the pressure and the ensuing expansion of the steam and oil. The expansion of the water being far in excess of the expansion of the oil, it is obvious that the disintegration of the oil into finely divided globules is nearly perfect. Escaping into the vaporizing chamber of the apparatus, to be presently described, in a foamy condition, consisting of globules or vesicles of the viscous cohesive liquid oil, containing the vaporized constituents, these globules or vesicles are broken up and dispersed by the confined vapors, which are then drawn off and condensed, while the asphaltic residuum falls to the bottom of the chamber. Though there is a thorough disintegration of the oil when the pressure is removed, the chemical affinity of the hydrocarbon elements is not destroyed, but only suspended for an infinitesimal period during the expanding action. By reason of the pressure and heat on the oil, containing a specific percentage of moisture in either of the forms indicated, I am enabled to drive off the distillates, and at the same time obtain asphalt and asphaltic products without subsequent treatment, after first having determined upon the amount of pressure and heat necessary for a specific product. But to more thoroughly insure the production of a certain grade of asphalt I may cause the heavier hydrocarbon ingredients to fall in the still chamber in a current of heat to govern, by controlling the temperature, the softness or hardness of the product sought.

The accompanying drawing represents the preferred form of a still for carrying out the process hereinbefore defined. It consists of

a vaporizing chamber 1, of necessary height, with which a fire box 2 is in communication. In the said fire box 2 is a coil 3, connected with a supply pipe 4 through which crude oil is delivered from a pump 5 to the coil; a steam pipe 6 is connected with said supply pipe, as is also a water pipe 7, such pipes serving to give to the crude oil the necessary moisture before it enters the coil 3. The mixture of oil and water in the coil 3, is heated, preferably by an oil burner 8, to a temperature sufficient to cause a free liberation of the hydrocarbon distillates, and a conversion of the water into steam. Such temperature ranges from 150° F. to 600° F., according to the density of the crude, and while the evolution of vapors occurs in proportion to the heat, there occurs concurrently a pressure as a result of such evolution of vapors, such pressure increasing proportionately with the increase in heat and the generation of vapors. The oil thus admixed, would ordinarily in cylinder distillation, foam to a considerable extent, but being confined, and under a steadily increasing pressure, no such action takes place during the subjection of the oil to pressure, until it is caused to discharge, when by the suddenness of the liberation of pressure the oil bursts forth, dissipating the volatile constituents. Such discharge occurs in the vaporizing chamber 1, through the rose 9, which is connected with the pipe 10, leading from the coil 3. On said pipe 10 is a pressure valve 11, fulcrumed in a lever 12, which is pivotally supported on said pipe, and on which is mounted a weight 12' adjustable relatively thereto. The adjustment of the weight on the said lever 12 regulates the pressure of the oil and water that is necessary to overcome the weighted valve 11, such pressure being indicated by the gage 13 on the pipe 10. When from the distillates or residual products it is found that additional heat is required to either vaporize the steam or decrease the penetrability of the asphalt, the damper 14 in the fire box 2 is opened and the damper 15 in the stack or flue 16 is closed. In this manner the products of combustion from the heat producing medium, are let into the vaporizing chamber to meet in their ascent the unvolatilized particles or remnants of oil that have not succumbed to complete disintegration by the original expansive force of the pressure. This is found desirable especially where the crude oil subjected to pressure is very dense and on account of such density the expansion ensuing upon liberation is not as great as with lighter crudes, even though the pressure is increased to meet this difficulty. Ordinarily the still is run with the damper 14 closed and flue damper 15 opened, whereby the heat or gas produced from combustion escapes to the atmosphere. In some cases it may be de-

sirable to use superheated steam or hot air in the vaporizing chamber 1, when a finer distilled product and a more tenacious asphalt is desired from the oil, that is obtainable by the rupture of the bubbles or vesicles upon removal of the high pressure. Superheated steam may be delivered to the vaporizing chamber through the nozzle 17 extending in the bottom of the still, such nozzle forming the terminus of a pipe 18 leading from a superheater 19 disposed within the fire box 2, and receiving heat from a suitable source such as an oil burner 20. Air may be delivered to the vaporizing chamber through the same nozzle 17, by closing the valve 21 in the pipe 18 and opening the valve 22 provided on an air pipe 23, which is connected with any suitable supply not shown. Obviously both valves 21 and 22 may be simultaneously opened to admit steam and air, where this is found necessary, in case of oxidation of the oils.

Should the delivery of the compressed oil body to the nozzle 17 be too great for ready discharge, the overflow or surplus oil will travel through pipe 24 to a collecting tank, after the valve 25 thereon has been opened. The distillates are drawn off from the vaporizing chamber 1, through a pipe 26, a suction being maintained by steam sprays issuing from jets 27 and 28. Said distillate conveying pipe 26 connects with a condenser in the form of a coil 29 submerged in a body of water, the condensed distillate being drawn off through a trap 30 and pipe 31 leading from the trap, which serves to prevent the passage of any uncondensed vapor into the collector. Such uncondensed vapor may be allowed to escape to the atmosphere through pipe 32, or the same may be drawn off by means of a suction pump 33, which also serves to draw the vapors from the vaporizing chamber 1. The asphaltic residuum is drawn off through the outlet pipe 34, leading from the bottom of the still.

According to the process described, the proportions of water added to the crude which does not naturally contain water, should preferably be from 1% to 3%, where an increased yield of distillates is desired. But where a residual product is sought, the percentage of water added should vary from 1% to 5%, according to experiments which show that these proportions are most economically efficient to thoroughly atomize the oil. It will be understood that a larger percentage of water added or naturally contained in the crude, will not vary the final results of the process in point of quality or quantity, but the time of treatment will be changed, that is lessened or prolonged according to temperature. These proportions will change, as shown by experiments, only as the gravity of the oil changes, so that for instance, where a 20 gravity oil is treated

the proportion used will be from 1% to 3%. The proportions will always vary directly as the gravity of the crude varies.

In treating oils by this process, the temperatures will also vary according to the gravity of the oil and the quantity of water. For instance, to separate water naturally contained in the crude, the temperature will vary in accordance with the proportions of water, which if it be from 1% to 3%, will require a temperature of from 300° F. to 460° F. For distillates and residues, the temperature is increased to properly vaporize the mixture, it ranging then from 300° F. to 600° F.

What I claim is:

1. The process of treating petroleum which consists in mixing with petroleum water, under pressure, then subjecting the mixture to a vaporizing temperature and a pressure of from 50 to 600 pounds per square inch, and thereupon allowing the vaporized mixture to escape in a vaporizing chamber.
2. The process of treating or vaporizing petroleum which consists in intimately mixing with the petroleum, under pressure, a quantity of water determinable by the gravity of the petroleum, then subjecting the mixture to heat sufficient to vaporize the same and to pressure above atmospheric pressure, then allowing the vaporized mix-

ture to expand in a heated chamber, and finally separating and condensing the vapors.

35

3. The process of treating petroleum or its derivatives which consists in mixing water with the petroleum or its derivatives, heating the mixtures, subjecting the mixture to pressure above atmospheric pressure, 40 and then relieving the pressure and collecting the products.

4. The described process for effecting a maximum vaporization of hydrocarbon oil by the expansible action of steam generated 45 from water mixed therewith, comprising confining a mixture of oil and water, heating the same under pressure, said pressure in part being produced by the volatilization of the mixture, the steam generating from 50 the water interacting in confinement with the oil and increasing the volatilization thereof, and thereafter relieving the pressure and discharging the mixture into a vaporizing chamber in the form of a finely 55 divided spray, the steam thereupon, by its expansive energy, acting to additionally break up the oil into vapors.

In testimony whereof I have set my hand in the presence of two witnesses.
